KEY STRUCTURE FOR TEAR STRIP CONTAINERS

Margaret Ruffin Wilkins, Greenville, S. C.

Application July 8, 1953, Serial No. 366,835

1 Claim. (Cl. 220—52)

This invention relates to an improvement in those types of keys adapted to remove tear strips from certain kinds of vacuum packed tins such as coffee tins. More particularly, the invention relates to a key having opposed double prongs between which the tear strip is positioned in such manner that it will not slip off the end of the key or become disengaged therewith.

Various types of keys have been devised for this particular use; however, either they are impractical to make because of the inordinate cost, they are subject to fracture easily, or they do not obtain the advantageous objectives of the instant invention.

It is also an object of the invention to provide a key of the type mentioned wherein such opposed pairs of projections terminate in relatively sharp points so that during winding of the tear strip on the key the latter has a positive means of traction which quickly overcomes the resistance of the tear strip to removal from the can.

A further object of the invention is the provision of a key of the type mentioned which can be fabricated of stamped metal at exceedingly low cost, and yet which will be comparatively durable and sufficiently strong to effectively remove such tear strips without twisting or breaking.

Other objects and advantages of the instant invention will be understood from the following description and the drawing forming a part hereof, wherein:

Figure 1 is a plan view of my improved key, picturing it as attached to the top of a sealed tin such as a coffee tin;

Figure 2 is a section view taken on the line 2—2 of Figure 1;

Figure 3 is a perspective view of the invention shown in Figure 1, illustrating the manner in which the tear strip is wound between opposed pairs of projections; and

Figure 4 is an enlarged perspective view of a portion of the key shown in Figure 3, illustrating the manner in which the opposed projections may be provided with the sharpened points to add to the tractive functions of the key.

Having now more particular reference to the drawings, the typical tin container is illustrated at 1. Such is usually provided with a concentric depression at the central portion thereof, herein designated at 2.

Viewing Figure 1, it will be readily appreciated that the entire key may be fabricated with a single stamping out of sheet metal of sufficient thickness to resist bending when the key is used. As a matter of fact, the sharpened edges, to be referred to in more detail hereinafter, can be formed by the same stamping process.

In so manufacturing the device it is, of course, provided with a handle 3 consisting merely of a rectangular formation provided with an enlarged opening 5. The opposite end of the key terminates in a projection or extension 6 which is suitable for attaching, by soldering or other medium, that end of the key to the top 2 of the can. As indicated at 7, a suitable crimping between extension or tip 6 of the key and the remainder

2

thereof appreciably weakens the interconnection therebetween. This enables the key to be bent upwardly, when desired for use, so that it breaks at this point from the extension 6 which, as stated, is permanently affixed to the can top. This operation is perfectly apparent from Figure 2 wherein the key is shown in solid line in its fixed and horizontal position and wherein it is depicted at B in a lifted or angular position approximately sufficient to break it from its secured extension 6.

10 The main body portion 8 of the key is provided with two opposed shoulders or triangular formations 10 and 11. Each of these terminate at their inner edges in points 12.

Between these shoulders is positioned a shank 15 provided with a slot 16, the latter being adapted for reception of the free end of the tip strip to initiate the winding again of the latter upon such shank 15.

It is seen that the inner faces 17 of the respective triangular formations or shoulders 10 and 11 are parallel to each other and thus form what might be termed retaining rims. Actually, although the entire structure just described is flat in formation the two triangular portions 10 and 11, together with the shank 15, form what might be viewed as a winding spool suitable for reception of the tear strip.

These triangular arms 10 and 11 with their respective points 12, also provide leverage for winding and serve to tighten, through the same leverage, the strip as it is wound around the shank 15 of the key, thus providing a uniform and smooth coil throughout the winding operation.

Thus the triangular formations 10 and 11, forming an integral part of the key, serve to contain the strip of metal therebetween, thereby eliminating the tendency of the strip to slip off the key in an unmanageable coil making further winding impossible. This operation should be readily understood by reference to Figure 3, wherein it is seen that the strip 20 is formed in a precise and even coil within the two triangular shoulders 10 and 11.

A modification of the invention is shown in Figure 4. Here each of the points 12 of the two opposed triangular formations 10 and 11 is sharpened somewhat, resulting in comparatively pointed projections 25. This may be done, as stated, either during the stamping process or the key can be honed at these points in a degree sufficient to render the same more pointed than those shown, for example, in Figures 1 and 3. With the four projections 12 sharpened somewhat in this manner it is to be appreciated that they provide considerably more traction against the usual smooth surface of the common type of vacuum tin. In any event, whether with points shown in Figure 1 or those shown in Figure 4, the projections 12 are such that they facilitate an immediate grasping of the surface of the can and an immediate tearing and winding effect upon the tear strip.

The operation of this invention should be apparent from the foregoing: The key is disengaged from its soldered tip 6, affixed to the can, and the metal strip on the side of the usual metal container is inserted through the slot 16. When the handle 3 of the key is turned the shaft or shank 15 and the four projections 12 are brought into play in a circular "walk around" the can, the strip being wound and retained within the triangular arms or rims 10 and 11 much in the same manner that wire cable is wound upon a spool. Leverage for winding and tightening is additionally furnished by the points of the projections 12 and pressure of these relatively sharp points against the side of the can. When the arc around the can is completed the key is discarded.

It is apparent also that this key can be manufactured in various sizes depending upon the size of the tin de-

sized to be used. The distance between the slot 16 and the end of the projections 12 may also vary with the circumference of the can, the controlling factor being provision of such distance as to contain the entire rolled strip within such projections.

It is to be understood that the instant invention exhibits two primary and critical factors not found in previous related devices. These are firstly, the ability to wind the tear strip upon the key without possibility of slippage axially therefrom, and secondly, the added traction supplied by the relatively sharp projections 12, the latter feature contributing materially to the more expeditious removal of such strip from containers of the type described.

While a preferred embodiment of the invention has been shown, it is to be understood that various modifications thereof may be resorted to without departing from the spirit and scope of the appended claim.

What I claim is:

In a key for removing a tear strip from a can, a main

15
20

body portion, a handle at one end of said portion, a severable tip at the other end thereof, a longitudinal slot in said body portion intermediate the ends thereof for the reception of the end of a tear strip, opposed 5 pairs of spaced triangular shoulders having facing parallel sides projecting from opposite sides of said body portion, with the ends of the slot in alignment with said parallel sides, the outermost ends of said shoulders terminating in relatively sharp points for engagement 10 with the surface of said can, said shoulders extending outwardly a substantial distance beyond the sides of said body portion and forming abutments between which a tear strip is rolled when removed from the can.
